CLAIM

The ornamental design for a pegboard bin, as shown and described.

DESCRIPTION

FIG. 1 is a perspective left, front, and upper view of a pegboard bin according to my new design;

FIG. 2 is a front elevation view of the pegboard bin of FIG. 1;

FIG. 3 is a rear elevation view of the pegboard bin shown in FIG. 1;

FIG. 4 is a right elevation view of the pegboard bin shown in FIG. 1;

FIG. 5 is a left elevation view of the pegboard bin shown in FIG. 1;

FIG. 6 is an upper elevation view of the pegboard bin shown in FIG. 1;

FIG. 7 is a lower elevation view of the pegboard bin shown in FIG. 1;

FIG. 8 is a perspective left, front, and upper view of a pegboard bin in accordance with another embodiment;

FIG. 9 is a front elevation view of the pegboard bin of FIG. 8;

FIG. 10 is a rear elevation view of the pegboard bin shown in FIG. 8;

FIG. 11 is a right elevation view of the pegboard bin shown in FIG. 8;

FIG. 12 is a left elevation view of the pegboard bin shown in FIG. 8;

FIG. 13 is an upper elevation view of the pegboard bin shown in FIG. 8; and,

FIG. 14 is a lower elevation view of the pegboard bin shown in FIG. 8.
